(57) **CLAIM**

The ornamental design for a vaporizer cartridge, as shown and described.

DESCRIPTION

FIG. 1 is a front perspective view of the vaporizer cartridge showing a first embodiment;

FIG. 2 is a rear perspective view of the vaporizer cartridge of FIG. 1;

FIG. 3 is a left side elevational view of the vaporizer cartridge of FIG. 1;

FIG. 4 is a right side elevational view of the vaporizer cartridge of FIG. 1;

FIG. 5 is a bottom plan view of the vaporizer cartridge of FIG. 1;

FIG. 6 is a top plan view of the vaporizer cartridge of FIG. 1;

FIG. 7 is a front elevational view of the vaporizer cartridge of FIG. 1;

FIG. 8 is a rear elevational view of the vaporizer cartridge of FIG. 1;

FIG. 9 is a front perspective view of the vaporizing cartridge showing a second embodiment;

FIG. 10 is a top plan view of the vaporizing cartridge of FIG. 9; and,

FIG. 11 is a front elevation view of the vaporizing cartridge of FIG. 9, the rear perspective view, the left side elevation view, the right side elevation view, the bottom plan view, and the rear elevation view being the same as in the embodiment of FIG. 1 and therefore not illustrated in the drawing disclosure for a second time.

The broken lines in the drawings depict portions of the vaporizer cartridge that form no part of the claimed design.
